UNITED STATES PATENT OFFICE.

JONATHAN ZENNECK, OF DANZIG-LANGFUHR, AND KARL VOLLMER, OF JENA, GERMANY, ASSIGNEES TO NORSK HYDRO ELEKTRISK KVAELSTOFAKTIESELSKAB, OF CHRISTIANIA, NORWAY, A CORPORATION OF NORWAY.

PRODUCTION OF LONG STABLE ELECTRIC ARCS.

1,063,760.

Specification of Letters Patent.

Patented June 3, 1913.

Application filed May 13, 1912. Serial No. 696,974.

To all whom it may concern:

Be it known that we, JONATHAN ZENNECK and KARL VOLLMER, subjects, respectively, of the King of Wurttemberg and the King of Prussia, residing, respectively, at Danzig-Langfuhr and Jena, Germany, have invented new and useful Improvements in the Production of Long Stable Electric Arcs, of which the following is a specification.

10 In the specification of Letters Patent No. 930,238 of August 3, 1909, granted to Messrs. Schönherr and Hessberger, is described the production of long stable electric arcs.

15 Our present invention relates to improvements in the production of the said arcs, whereby the efficiency of the said arcs for producing reactions in gases is considerably increased.

20 According to the present invention the arc produced as described in the said Letters Patent when employing an enveloping current of gas possessing a whirling motion is subjected to the action of a magnetic field and the best results are obtained when the gases are introduced into the tubular furnace tangentially, so that a whirling motion is produced as described in the said specification. The magnetic field can be arranged in any suitable manner, for instance the lines of force may be caused to run parallel or nearly parallel with the arc which could be readily obtained by surrounding the reaction tube or passage with 25 a coil of wire carrying a current or the lines of force may be caused to pass at right angles to the arc and this latter arrangement appears to give the best result. Such a field can readily be created by the use of 30 two or more coils with their axes at right angles to the tube or passage containing the arc or permanent magnets or the like can be employed.

Referring to the accompanying drawings, Figure 1 illustrates a portion of the arc K 45 produced in the large tube A B according to the process of Letters Patent No. 930,238 by means of a current of air with a whirling motion around the arc. Fig. 2 shows the same arc, but subjected to the modification 50 according to the present invention, namely by being subjected to the magnetic field of the pairs of magnetic poles P P, Q Q, R R and S S. The gases nitrogen and oxygen treated in the arc thus subjected to the action 55 of magnetic fields are converted to a greater extent into oxides of nitrogen, so that a higher yield of these products is obtained.

Now what we claim is:—

1. The improvement in the production of 60 long stable electric arcs by means of an enveloping current of gas possessing a whirling motion which consists in subjecting the said arc to the action of magnetic fields.

2. The improvement in the electric production of endothermic reactions in gases which consists in maintaining a current of the gas possessing a whirling motion around an electric arc which is subjected to the action of a magnetic field. 65

In testimony that we claim the foregoing as our invention, we have signed our names in presence of two subscribing witnesses.

JONATHAN ZENNECK.
KARL VOLLMER.
